ROLL CHANGING DEVICE

Mathias Langen, Parkstone, Dorset, England, assignor to The Loewy Engineering Company Limited, London, England, a corporation of Great Britain

Filed July 8, 1954, Ser. No. 442,041

Claims priority, application Great Britain July 9, 1953

2 Claims. (Cl. 254—106)

This invention relates to a roll changing device for a rolling mill and, in particular, to a roll changing device in which the rolls are inserted into the mill stand or withdrawn therefrom by being moved sideways with respect to the mill stand.

Roll changing devices of this type are particularly useful in connection with rolling mills in which the separating forces are considerable, such as four-high mills, and where, consequently, large screwdown gears are required, as the sideways movement of the rolls makes it possible for the rolling mill housings to have closed tops, whereby their strength and rigidity are greatly improved, particularly in that part which accommodates the screwdown gear.

A roll changing device of the type above referred to comprises generally a movable support or carrier in the form of a sledge receiving the rolls, together with any attachments, such as their bearings or chocks, the sledge being adapted to be moved sideways with respect to the rolling mill stand along a track to a point outside and adjacent the mill stand where the rolls can be taken off the sledge and replaced by another roll assembly.

The weight of a roll assembly to be carried by the sledge is often very heavy, and the forces required for moving the sledge with a roll assembly loaded thereon are therefore considerable.

Various proposals have been made in the past for displacing the sledge of a roll changing device sideways into and out of a rolling mill stand. None of these was, however, quite satisfactory.

Movement of the sledge by ropes connected to the lifting tackle of a travelling crane lacked precise control, a disadvantage which was particularly apparent when moving the rolls into position inside the mill stand. The use of ropes necessitated also the arrangement of pulleys at both sides of the mill stand. This was inconvenient because space at least on one side of the mill is always restricted by the rolling mill drive.

It has further been proposed to provide a roll changing device with shifting means, permanently connected to the sledge, whereby a more precise control of its movement is achieved.

These means consisted either of a nut traversing a threaded spindle, or of a hydraulic cylinder with a double-acting piston displaceable therein. The length of the spindle and that of the cylinder were determined by the distance between the two extreme positions of the sledge. If this distance was great, as in the case of mills having rolls of great barrel length, the spindle and the cylinder became very expensive and cumbersome. Building up a long cylinder from a number of shells joined endwise together was found to be inexpedient for various reasons.

It is an object of the present invention to provide a roll changing device for rolling mill stands comprising a movable support or a carrier in the form of a sledge,

2

having improved means for shifting said sledge in or out of the rolling mill stand.

The shifting means according to the invention are of the hydraulic type and they comprise accordingly a pressure-fluid cylinder and a double-acting piston. Of these two elements, one is connected directly to the sledge, while the other can slide along a track and be immobilized at spaced-apart and pre-selected points on that track. The track for the slideable element may be the same as that for the sledge.

The element connected to the sledge is preferably formed by the double-acting piston, and the slideable element formed by the cylinder, although the arrangement can be reversed. Displacement of the piston in the cylinder, with the cylinder locked to the track, will result in a corresponding displacement of the sledge along its track. Displacement of the piston in the cylinder, with the cylinder free to slide along the track and the sledge loaded with a set of rolls, will result in a corresponding displacement of the cylinder along the track, as the piston and the sledge will be immobilized by the weight of the rolls on the sledge. In this way, the cylinder can be moved towards or away from the mill stand by a distance equal to the stroke of the piston.

This arrangement and mode of operation permits the movement of the sledge along its track by a total distance which is a multiple of the stroke of the piston relative to the cylinder, simply by alternately admitting pressure-fluid to opposite sides of the piston and freeing or locking the cylinder to the track at alternate strokes of the piston.

It will be realized that, in this way, the length of the stroke of the piston, and accordingly the length of the cylinder required for moving the sledge in or out of the mill stand by a given distance, can be greatly reduced and need only be a fraction of the stroke which would otherwise be required to move the sledge by the same distance. The shifting means according to the invention are therefore comparatively simple and inexpensive and do not require excessive space for their accommodation adjacent the rolling mill stand.

According to a further feature of the invention, control means are provided for alternately admitting pressure-fluid to opposite sides of the double-acting cylinder.

Locking means may be provided for immobilizing the slideable elements at spaced-apart and pre-selected points along its track. These locking means may be in the form of pivoted pawls engageable in notches provided at spaced-apart and pre-selected points along the track.

The invention will now be described by way of example with reference to the accompanying drawings, which show one embodiment of the invention:

Fig. 1 is a front elevation showing a roll changing device according to the invention applied to a four-high rolling mill, with its hydraulic shifting means in section.

Figs. 2, 3, 4, 5 and 6 show, on a somewhat larger scale, various positions which the hydraulic shifting means take up during a movement away from and towards the rolling mill stand.

Fig. 7 is a plan view of the roll changing device of Fig. 1.

Fig. 8 is a cross-section through the hydraulic shifting means according to line 8—8 of Fig. 1.

Fig. 9 is a cross-section through the hydraulic shifting means according to line 9—9 of Fig. 1.

Referring to Fig. 1, the rolling mill, to which the roll changing device according to the invention is applied, is generally designated with 10. It is shown here as a four-high mill comprising work rolls 11, 12 and back-up rolls 13, 14. The chocks for the four rolls 11 to 14 are not separately shown as they are immaterial for the present

invention; they are located within the spaces 15 and 16 at both sides of the rolls. The four rolls and their chocks form together the roll assembly 17 and will be referred to as such in the following description.

The roll changing device comprises a sledge 20 which is adapted to receive the roll assembly 17 and which can be moved together with a roll assembly into and sideways out of the rolling mill stand 10. The sledge 20 is movable along a track 21 by hydraulic shifting means generally designated by 22. These means comprise a cylinder element 23 and a double-acting piston element 24. The piston has a piston rod 25 which, at its end, carries a hook 26 adapted to enter a notch 27 in the sledge 20. The cylinder 23 is displaceable along the same track as the sledge 20, and its base-plate 28 is provided to this end with shoes 29 slidable along the track 21 (Fig. 9).

Attached to the cylinder 23, at both of its sides, are double-acting pawls 30 which can swing in opposite directions about pins 31 formed on cylinder bosses 32 (Fig. 8). These pawls co-operate with notches 33 arranged on the track 21 at stations A, B and C which are spaced-apart by a distance equal to the stroke length of the piston 24. At each of these three stations there are on each side of the track two notches 33 which form together dove-tails 34 on the track 21. The notches 33 on the mill stand side of the dove-tail 34 are engaged by the pawls 30 during the inward travel of the sledge and the notches at the opposite side of the dove-tail at the outward travel of the sledge. Each pawl 30 has accordingly two lugs with inclined faces 35 which can be alternately made to engage one of the two notches 33 at opposite sides of a dove-tail 34 by tilting a pawl 30 about its pivot pin 31. Tilting of the pawls 30 is effected by means of weighted rocking arms 36 attached to the pawls. The transition from a notch 33 to the upper level of the track 21 is formed by a slope 37 which acts as a cam-face for tilting a pawl on its becoming disengaged from a notch, so that the pawl can ride freely along the track 21 until it drops into the next notch 33.

Hydraulic pressure-fluid is supplied to the cylinder 23 by means of flexible hoses 38, 39 which are connected at their ends to fixed pipes 40, 41 and 42, 43 respectively. The admission of pressure-fluid to the cylinder 23 is controlled by a hand-operated valve 44, or any other suitable means. A pump, not shown here, is provided as a source of supply of pressure-fluid.

The stops 45 and 46 at opposite ends of the track 21 prevent over-travel of the shifting means 22 in both directions. Stops 45, 46 co-operate with ears 47 protruding from the four corners of the base-plate 28.

The track 21 for the shifting means 22 is preferably located in a pit below floor level, a second somewhat deeper pit being provided alongside the track for accommodating the loops formed by the flexible hoses 38 and 39 (Figs. 8 and 9).

The operation of the hydraulic shifting means 22 will now be described in detail with reference to the Figs. 2, 3, 4, 5 and 6:

Before the removal of a roll assembly 17 from the mill stand 10, the parts have the positions shown in Fig. 2, with the hydraulic cylinder 23 being immobilized on the track 21 through the pawls 30 engaging the notches 33 at A. In this position, the ears 47 are close to the stops 45 on the track 21, although not in actual contact with them.

Pressure-fluid is now admitted to the left of piston 24, whereby the latter is moved towards the right. This causes the sledge 20, with a roll assembly 17, to be pulled out of the rolling mill stand 10 by a distance corresponding to the stroke of the piston. The positions of the piston 24 at the end of the stroke and of the sledge hook 26 are indicated in dotted lines in Fig. 2. This step forms the first pull-out movement of the sledge 20.

The control valve 44 is now operated so as to reverse the pressure and exhaust connections to the cylinder 23

and pressure-fluid is, therefore, admitted to the right of the piston 24, whilst the pressure-fluid on the left of the piston is exhausted. This results in a movement of the cylinder 23 to the right, i.e., away from the mill stand 10, with the piston 24 remaining stationary, as the weight of the roll assembly carried by sledge 20 is much in excess of that of the cylinder 23 and immobilizes the sledge and the piston. During this movement, the pawls 30 ride over the slopes 37 of the notches 33 whereby the pawls are tilted slightly. The stroke of the cylinder 23 during this step has the same length as that of the piston 24 during the first pull-out movement, the cylinder 23 occupying at the end of its stroke the position shown in Fig. 3 with the pawls 30 engaging the notches at station B, whereby they immobilize the cylinder in its new position.

The hydraulic shifting device 22 is now ready for another stroke of the piston 24. This is effected by reversing again the connections of the hydraulic cylinder 23 by means of the hydraulic control valve 44, pressure-fluid being admitted to the left of the piston 24 and exhausted from the right, in the same way as during the first step. The piston, together with the sledge 20, is thereby moved away from the mill stand 10 by another stroke length, its position at the end of the stroke and that of the sledge hook 26 being indicated in dotted lines in Fig. 3. This is the second pull-out movement.

The hydraulic pressure-fluid connections are thereupon again reversed by means of the control valve 44 which results in the displacement of the cylinder 23 along the track 21 whilst the sledge 20 remains stationary owing to the weight of the roll assembly 17 (Fig. 4). The cylinder 23 moves until the pawls 30 enter the notches 33 at station C. In this position, the ears 47 at the right-hand end of the base-plate 28 are very close to the stops 46, although not in actual engagement with them.

This is followed by a further reversal of the pressure-fluid connections, resulting in a displacement of the piston 24 along the track 21 whilst the cylinder 23 is immobilized through the pawls 30 having entered the notches at station C. This forms the third pull-out movement.

The sledge 20 is now in a position in which the roll assembly 17 can be lifted therefrom and replaced by another roll assembly which is to take the place of the first one in the mill stand 10.

For the return movement of the sledge 20, pressure-fluid is admitted to the right-hand side of piston 24. This will cause the cylinder 23 to move a short distance to the right until the ears 47 and the stops 46 are in engagement with each other (Fig. 5), whereby the pawls 30 are caused to become disengaged from their notches 33 at C. The pawls 30 can then be swung about their pivot pins 31 by means of the actuating levers 36, as shown in Fig. 5. Further admission of pressure-fluid to the right-hand side of the piston 24 causes the piston, together with the sledge 20, to move to the left. Fig. 5 shows the piston 24 and the sledge 20 in their positions at the end of this stroke. This completes the first push-back movement.

The cylinder 23 is now moved towards the mill stand 10 by reversing the position of the control valve 44, with the sledge being immobilized owing to the weight of the roll assembly. The cylinder travels back until its pawls 30 enter the notches 33 at B. The alternate movements of piston 24 and cylinder 23 are repeated, as indicated in Fig. 6, until the cylinder has reached the position in which its pawls 30 enter the notches 33 at A, and until the sledge 20 is inside the rolling mill stand 10.

It will be seen that the entire stroke of the sledge 20 between its two extreme positions is carried out in three steps. This results in reducing the stroke required from the piston and, thereby, also the length of the cylinder, by two-thirds, with a consequent simplification in the arrangement of the shifting means.

It is preferred to move the cylinder 23 at a higher

speed than the piston 24 in order to reduce the intervals between successive movements of the sledge 20 and to reduce the total time for the exchange of the roll assembly 17. As much less power is required for the movement of the cylinder 23 than for the movement of piston 24, together with the sledge and a roll assembly, a pump of the variable delivery type is very well suited to these conditions as this type of pump gives a high output at slow speeds, and a small output at high speeds.

The full stroke of the sledge between its two extreme positions can be sub-divided into any suitable number of steps, and it will be apparent that with the arrangement according to the invention it is possible to move a roll changing device over a long distance with the aid of shifting means having a comparatively short stroke.

The invention is capable of embodiments other than those shown here. The operation of the shifting means can be made automatic by providing electric limit switches alongside the track which actuate the hydraulic control valve for the pressure-fluid if and when the cylinder and the piston have reached predetermined positions along the track. Furthermore, the arrangement of piston and cylinder relative to the sledge and track can be reversed and the sledge be connected to the cylinder and the piston be provided with the pawls which lock it to the track.

What I claim is:

1. In combination, a horizontal track and self-propelled shifting means carried by said track for shifting a load along said track, said shifting means comprising a double acting pressure fluid operated cylinder member and a piston member, means adapted for securing said piston member to a load, the combined weight of said piston member and said load exceeding the weight of said cylinder member whereby said piston member and said load are normally stationary relative to said cylinder member, guide means provided between said track and said cylinder member to direct movement of said cylinder member on said track toward and away from said load, said track being provided with a plurality of pairs of cam faces, each of said pairs of cam faces consisting of a pair of notches, each of said notches being inclined in an opposite direction from a vertical transverse plane through said track and each of said pairs of cam faces being spaced apart from the immediately adjacent of said pairs of cam faces at a distance less than the total distance said load is to be shifted, and latching means pivotally mounted on said cylinder member for movement to a first and to a second position and to correspondingly determine the direction of sliding of said piston and said cylinder member, said latching means when moved to said first position consecutively engaging the cam faces on said track which are located to the same side of said vertical transverse planes whereby engagement of said latching means with said last mentioned cam faces causes one of said members to move in one direction relative to the other member and shift said load upon admission of pressure fluid to one of the sides of said cylinder member and causes said cylinder member to move away from said load in the same direction upon subsequent admissions of pressure fluid to the opposite side of said cylinder member to reposition said cylinder for further move-

ment of said load, and said latching means when moved to said second position engaging consecutively the cam faces on said track which are located on the opposite side of said vertical transverse planes to cause said piston member to move in the opposite direction upon admission of pressure fluid to one of the sides of said cylinder member and cause said cylinder to move toward said load in said opposite direction upon admission of pressure fluid to the opposite side of said cylinder member.

2. In combination, a horizontal track and self-propelled shifting means carried by said track for shifting a load along said track, said shifting means comprising a double acting pressure fluid operated cylinder member and a piston member, means adapted for securing one of said members to a load, the combined weight of the member connected to said load and of said load exceeding the weight of the other member whereby the member connected to said load and said load are normally stationary relative to the other member, guide means provided between said track and one of said members to direct movement of one of said members on said track toward and away from said load, said track being provided with a plurality of pairs of cam faces, each of said pairs of cam faces consisting of a pair of notches, each of said notches being inclined in an opposite direction from a vertical transverse plane through said track and each of said pairs of cam faces being spaced apart from the immediately adjacent of said pairs of cam faces at a distance less than the total distance said load is to be shifted, and latching means pivotally mounted on one of said members for movement to a first and to a second position and to correspondingly determine the direction of sliding of said piston and said cylinder member, said latching means when moved to said first position consecutively engaging the cam faces on said track which are located to the same side of said vertical transverse planes whereby engagement of said latching means with said last mentioned cam faces causes one of said members to move in one direction relative to the other member and shift said load upon admission of pressure fluid to one of the sides of said cylinder member and causes the other of said member to move away from said load in the same direction upon subsequent admissions of pressure fluid to the opposite side of said cylinder member to reposition said member for further movement of said load, and said latching means when moved to said second position engaging consecutively the cam faces on said track which are located on the opposite side of said vertical transverse planes to cause one of said members to move in the opposite direction upon admission of pressure fluid to one of the sides of said cylinder member and cause the other of said members to move toward said load in said opposite direction upon admission of pressure fluid to the opposite side of said cylinder member.
